UNITED STATES PATENT OFFICE.

PAUL F. WILLIAMS, OF CHICAGO, ILLINOIS, ASSIGNEE TO G & W ELECTRIC SPECIALTY CO., OF CHICAGO, ILLINOIS, A CORPORATION OF ILLINOIS.

CONNECTING DEVICE FOR ELECTRIC CONDUCTORS.

1,225,300.

Specification of Letters Patent.

Patented May 8, 1917.

Application filed December 11, 1911. Serial No. 664,916.

To all whom it may concern:

Be it known that I, PAUL F. WILLIAMS, a citizen of the United States, residing at Chicago, in the county of Cook and State of Illinois, have invented a certain new and useful Improvement in Connecting Devices for Electric Conductors, of which the following is a full, clear, concise, and exact description, reference being had to the accompanying drawings, forming a part of this specification.

My invention relates to improvements in potheads, and has as its principal object the improvement of the design of cable potheads, particular reference being had to the inlet and outlet structures. A further object is to provide an improved form for the body of the pothead.

Further objects reside in the particular combination and arrangement of parts hereinafter described.

Referring to the accompanying drawings, Figure 1 is a front elevational view partly in section, showing my improved pothead as designed for a three conductor cable;

Fig. 2 is a top plan view with the cover removed;

Fig. 3 is a front elevational view partly in section of my improved pothead, also for a three conductor cable, one outlet being omitted, but illustrating a different form of outlet structure at the point where the conductors leave the pothead;

Fig. 4 is a detail of the outlet structure shown in cross section in Fig. 3, Fig. 4 being also in cross section and illustrating the method of operating this outlet structure;

Fig. 5 is a vertical cross sectional view of my improved form of pothead as designed for a single conductor cable, the body of the pothead being provided with certain modifications which obviously might be employed in the form shown in Figs. 1 and 3, if so desired;

Fig. 6 is a vertical cross sectional view of Fig. 1, taken on the line 6-6, and illustrates my improved form of inlet structure and a modification of the lower part of the pothead to accommodate the same;

Fig. 7 is a cross sectional view on lines 7-7 in Fig. 6, further illustrating the im-

proved inlet structure and its relation to the body of the pothead.

Throughout the various views the same part is indicated by the same reference character.

Referring more particularly to the drawings, 1 is the body of my three conductor type of pothead, as shown in Figs. 1, 2 and 3, preferably made of cast iron. 2 is a removable cover mounted on the body 1, and provided with bolts 3 carrying nuts 4, which engage with lugs 5 on the body 1 in order to clamp the cover and body closely together. The body 1 is cylindrical in its upper portion, as is obvious from Fig. 2, and below the cylindrical portion is a downwardly contracting conical portion 6, provided with apertures through which the conductors leave the pothead. Depending from the portion 6 is a second conical portion 7 having however a more gradual taper. The lower end of portion 7 has a central aperture for the admission of the cable. The individual conductors of the cable are spread within the pothead and led out through the apertures in the portion 6, their arrangement and appearance being clearly illustrated in Fig. 2. Surrounding each of the apertures in the portion 6 on the outside of the pothead is a flange 8. Passing through each aperture and guided by the wall of the pothead and the flange 8 is a perforated insulating bushing 9 having at its outer end a cup or bell shaped portion 10. The inner end of the bushing 9 projects within the pothead as illustrated clearly in Figs. 1 and 2. Within the bushing 9 is a conducting sleeve 11 provided at its inner end with a socket 12 for receiving the end of the cable conductor as 13. The sleeve 11 is provided with an exterior ridge 14, which guides it in the bushing 9 and helps retain it in proper position. At the inner end of the bushing 9 are screw sockets for retaining screws 15 which bind the sleeve 11 to the bushing 9 and retain the sleeve in proper position. The bushing 9 and the flange 8 are provided with registering grooves as 16 for receiving cement or grout for retaining the bushing in position. Screws not shown may also be used if de-

80

100

sired to assist the cement in holding the bushing in place.

Up to this point the description of the form shown in Fig. 1 is identical with that shown in Fig. 3. It is obvious, however, that applicant provides means for connecting and disconnecting the exterior conductor to the conductor within the pothead, and these devices are not alike except in the 10 sleeve 11. As appears in Fig. 1, sleeve 11 has an outer socket 17 which is adapted to receive a spring plug 18 which is supported on a conducting element 19. Element 19 is provided with a screw threaded inner portion and carries thereon a tapering piece 20. Surrounding the piece 20 is a conducting sleeve 21, which has a bore fitting that of the piece 20, and is provided at its outer end with screw threads adapted to engage 20 the mating threads on the outer end of the sleeve 11. Sleeve 21 is provided with lugs 22 which rest in sockets in the insulating sleeve 23. Thus when 23 is turned the conducting sleeve 21 is turned with it, either 25 to draw the member 20 and its connected plug 18 into close contact with the sleeve 11, or else to release the two parts so that the exterior conductor may be withdrawn from connection with the cable conductor. 30 The element 19 is surrounded by an insulating member 24. 19 is also provided with a socket for receiving the exterior conductor.

Referring more particularly to Fig. 3, I 35 provide in this case also the socket member 19 having a socket for connecting with the exterior conductor, and also having a plug member attached to its inner end. As shown more clearly in Fig. 4 this plug member 25 is connected to member 19 by means of screw threads, and at its inner end is provided with a groove 26 which is adapted to coöperate with a projecting pin 27 on the inner surface of the sleeve 11, thus 40 forming a bayonet connection. It will be apparent that an insulating piece 28 is provided covering the member 19. The piece 28 corresponds in some measure to the element 24 in Fig. 1, but is of somewhat different 45 shape and at its inner end is so formed as to fit closely against the flaring end of the member 10. In Fig. 3 there is no member corresponding to element 23 of Fig. 1.

Referring more particularly to Figs. 6 55 and 7, I have shown therein my improved arrangement for introducing the cable into the pothead. As appears in these figures 29 is the lead sheath of the cable which is surrounded by a threaded plug or closure 30, which contains a cone shaped gasket of suitable material. As shown, the plug 30 is provided with screw threads both on its inner and outer surfaces, the outer series of screw threads engaging a corresponding thread on 60 the inner surface of the lower wall 7 of the

pothead. Plug 30 also has a projecting flange 32 which engages the wall 7. The interior screw threads of the plug 30 receive the correspondingly threaded ring 33 which screws into the plug 30 compressing the gasket 31. 70 The ring 33 together with the upstanding parallel posts 34 and the upper ring 35, which are all cast integrally with each other, form a spider for clamping and supporting the inner end of the cable sheath as shown 75 at 29'. The inner end of the cable sheath is belled out and fitted over the upper ring 35. A detachable ring 36 is then clamped down on the end of the cable sheath by means of screws 37 holding the sheath 80 rigidly in place. The wall 7 inclines outwardly from the plug 30 while the upper rings 35 and 36 are of the same outer diameter as the lower ring 33. Consequently there is a space between the wall 7 and the 85 upper rings 35, 36 and the end of the cable sheath. In practice the interior of the pothead is filled with insulating oil or compound and with the improved design which I have illustrated the compound falls down 90 into the lower end of the pothead completely surrounding the inner edge of the cable sheath and extending some distance below it, thus effectually preventing the access of moisture to the interior insulation of 95 the cable.

In Fig. 5, I have shown a pothead body, which if desired may also be used in the modifications shown in Figs. 1 and 3. In Fig. 5 the lower part of the pothead 40 is 100 made of porcelain. Attached to the upper part of the porcelain is a cast iron piece 41 having a removable cover 42, also of cast iron. The part 41 is provided with an outstanding flange 43, surrounding an aperture 105 adapted to receive outlet devices similar to those shown in Figs. 3 and 4.

Owing to the small space in the form shown in Fig. 5 and the consequent sharp angle upon which the conductor would need 110 to be bent, I provide a casting 46 which has a central aperture for receiving the cable conductor and a shank or arm 47 adapted to connect with the sleeve 11.

It will be obvious that the inlet structure 115 shown in Figs. 6 and 7 might be used in the form shown in Fig. 5 if so desired, but as the form of Fig. 5 is for a single conductor cable, in practice this would probably not be desirable or necessary, and it 120 has not been so shown. It will be obvious also that the outlet devices of the form shown in Fig. 1 might also be used in Fig. 5. The forms shown in Figs. 1, 2 and 3 are provided with bosses 11, by which the 125 pothead may be properly supported. Similar lugs or bosses may be placed on the form shown in Fig. 5 if so desired, but owing to the lighter weight of the form of Fig. 5 this might not be necessary. 130

All the forms of my device shown are designed to have insulating compound poured into them after the connections are made. Such compound is shown in place in Figs. 1, 3, 5 and 6.

Having thus described my invention, what I claim is:

1. A pothead comprising in combination, a casing having an aperture, a perforated closure for said aperture, said closure being provided with threads whereby the same is secured to the casing, said closure being adapted to receive a cable and having a tapering cut-away portion largest at its inner end, and a ring adapted to fit into the inner end of said tapering cut-away portion, said ring and closure being provided with threads whereby the same are secured together.

2. A pothead comprising in combination, a casing having an aperture, a perforated closure for said aperture, said closure having the outer end portion of its bore of substantially the same size as a cable sheath, and having the inner end portion of its bore larger than a cable sheath, and a ring having a screw-threaded connection with the inner end of said closure, said ring being adapted to fit within the enlarged bore of said closure and also adapted to fit closely upon said cable sheath.

3. A pothead comprising in combination, a casing having an inlet aperture, a closure for said aperture provided with an opening for receiving a cable sheath and having a cut away portion for receiving a ring also surrounding said cable sheath, posts carried on said ring and supporting a second ring above said first named ring, and a third ring detachably secured to said second ring.

4. A pothead comprising in combination, a casing having an aperture, a perforate closure for said aperture, said closure being adapted to receive a cable sheath, and holding means within the casing for engaging the cable sheath at a place separated from the place of engagement by said closure.

5. The combination with a casing having an aperture, of a perforate closure for said aperture, said closure having an aperture for a cable sheath, and holding means within the casing for engaging the turned-back end of the cable sheath, said holding means comprising members for engaging both sides of the cable sheath at a place separated from said closure.

6. A pothead comprising in combination, a casing having an outlet aperture, a tube or bushing having its outer end flared mounted in said aperture, a conducting socket member mounted within said bushing, an insulating member carrying a conducting plug for connection with said sleeve, a clamping ring surrounding said plug member, and a second insulating member surrounding said ring for operating the

same, said second mentioned insulating member inclosing the first mentioned insulating member and in turn being inclosed by the flaring end of said bushing.

7. In a pothead the combination of a casing having an aperture, a closure for said aperture having an opening adapted to receive a cable sheath, a ring adapted for connection with said closure, and a pair of annular clamping members carried by said ring but separated therefrom, said clamping members being arranged within the casing and adapted to engage and clamp the turned-back end of the cable sheath, one of said clamping members being integral with said ring.

8. In a pothead, the combination with the casing having an aperture, of a closure for said casing having a perforation for a cable sheath, a ring carried by said closure and provided with members extending longitudinally of the cable, and a pair of clamping rings carried by said longitudinally extending members, said clamping rings being adapted to engage and clamp between them the outwardly extending edge of the cable sheath.

9. In a pothead, the combination of a casing having an outlet aperture, a tubular bushing for said aperture, said bushing having a flaring outer end, metallic connecting devices in said bushing, and a rotatable insulating member for the outer end of said connecting devices, said member being covered by said flaring end of said bushing and arranged to operate said connecting devices by its rotation.

10. In a pothead, the combination with the casing of a downwardly facing aperture, a downwardly extending bushing fitted to said aperture and having a flaring outer end, and connecting devices and insulating members therefor, one of said connecting devices being rotatable with respect to the other and shielded by said flaring end and being connected for operation by one of said insulating members.

11. In a pothead, the combination of a casing having a downwardly extending outlet aperture, a bushing extended through said aperture and having a flaring outer end, metallic connecting devices for connecting conductors with one another, said connecting devices being located in part in said bushing and insulating means for covering the lower end portion of said connecting devices, said covering means being protected by the flaring end of said bushing.

12. In a pothead, the combination of a casing provided with a downwardly extending outlet aperture, an insulating bushing extended through said aperture and having a flaring outer end, metallic connecting devices located in part within said bushing and in part projecting from the lower end of the

- same, said connecting devices being adapted for operation to permit the connection and disconnection of conductors, and an adjustable insulating member surrounding said 5 projecting portion of said connecting devices and engaging the same so as to permit the operation of said devices by the adjustment of said member, said member being located below and being protected by said 10 bushing and its flaring end.
13. In a pothead the combination with the casing, of a downwardly facing aperture, a downwardly extending bushing fitted to said aperture and having a flaring outer end, a 15 socket member mounted in said bushing, a member carrying a plug, a rotatable member connecting the plug and the socket, said member having a portion which extends into the flared portion of the bushing, and 20 the member which carries the plug having a portion which extends into the rotatable member.
14. In a pothead, the combination of a casing having a downwardly extending outlet aperture, an insulating bushing extending through said aperture, metallic connecting devices located in part within said bushing and in part projecting from the lower end of the same, and means for protecting and insulating the aforesaid projecting end portion of said connecting devices. 25
15. In a pothead the combination of a casing having a downwardly opening aperture, an insulating bushing extending 30
- 35
- through said aperture, metallic connecting devices located in part within said bushing and having their lower end portions projecting from the same, said connecting devices being adapted for the connection and disconnection of conductors and constructed 40 for such operation by a relative rotary movement, a rotary insulating member outside of the aforesaid projecting portion of said connecting devices, said member engaging said devices so as to operate the same 45 by its rotary movement, and means for covering and protecting said rotary insulating member.
16. In a pothead the combination with a casing of a downwardly extending bushing 50 having a flaring outer end, a member having a portion extending toward the flared portion of said bushing, contact making elements carried by said bushing and said member, a member positioned between said 55 downwardly extending bushing and said first mentioned member, said member having a portion projecting into the flared portion of said bushing and being recessed at its opposite end to receive the end of the 60 first mentioned member which projects toward the flared end of said bushing.

In witness whereof, I hereunto subscribe my name this 28th day of November A. D. 1911.

PAUL F. WILLIAMS.
